US0D1083680S

(12) **United States Design Patent** (10) **Patent No.:** **US D1,083,680 S**
(45) **Date of Patent:** **** Jul. 15, 2025**

(54) **MOTORCYCLE**

(71) Applicant: **ZHEJIANG TAOTAO VEHICLES CO., LTD.**, Lishui (CN)

(72) Inventors: **Rong Wu**, Xianning (CN); **Jianbing Wu**, Xianning (CN); **Guofu Zou**, Xianning (CN); **Zhihui Gan**, Xianning (CN); **Meijun Li**, Xianning (CN); **Kai Xie**, Xianning (CN); **Daoqing He**, Xianning (CN); **Xubin Ding**, Xianning (CN); **Pengju Li**, Xianning (CN); **Zhipeng Wang**, Xianning (CN); **Xiasheng Sun**, Xianning (CN); **Han Xu**, Xianning (CN)

(73) Assignee: **ZHEJIANG TAOTAO VEHICLES CO., LTD.**, Lishui (CN)

(**) Term: **15 Years**

(21) Appl. No.: **29/918,039**

(22) Filed: **Nov. 24, 2023**

(30) **Foreign Application Priority Data**

Aug. 15, 2023 (CN) 202330521684.X
